DESIGN FOR A CLOTH MEASURING MACHINE

George S. Rosborough, Webster Groves, Mo., as-
signor to The Measuregraph Company, St.
Louis, Mo., a corporation of Delaware

Application November 5, 1934, Serial No. 53,898

Term of patent 14 years

To all whom it may concern:

Be it known that I, George S. Rosborough, a citizen of the United States, residing at the city of Webster Groves, in the county of St. Louis and State of Missouri, have invented a new, original, and ornamental Design for a Cloth Measuring Machine, of which the following is a specification, reference being had to the accompanying drawing, forming a part thereof. The essential part of the design is that part appearing above the elongated base portion which is not conspic-

uously displayed when the device is operatively mounted.

Fig. 1 is a perspective view looking toward the front and one side of a cloth measuring machine showing my new design, and

Fig. 2 is a perspective view looking toward the rear and opposite side of the same.

I claim:

The ornamental design for a cloth measuring machine, as shown.

GEORGE S. ROSBOROUGH.
